UNITED STATES PATENT OFFICE.

ARGYLE CAMPBELL AND ALBERT E. ZIMMER, OF CHICAGO, ILLINOIS, ASSIGNORS TO
ENTERPRISE RAILWAY EQUIPMENT COMPANY, OF CHICAGO, ILLINOIS, A CORPO-
RATION OF ILLINOIS.

TANK-CAR VALVE AND OPERATING MECHANISM THEREFOR.

Application filed April 6, 1921. Serial No. 458,959.

To all whom it may concern:

Be it known that we, ARGYLE CAMPBELL and ALBERT E. ZIMMER, citizens of the United States, residing at Chicago, in the county of Cook and State of Illinois, have invented a certain new and useful Improvement in Tank-Car Valves and Operating Mechanism Therefor, of which the following is a full, clear, concise, and exact description, reference being had to the accompanying drawings, forming a part of this specification.

This invention relates to improvements in tank car valve and operating mechanism therefor.

One object of the invention is to provide an efficient shut-off valve mechanism especially adapted for railway tank cars and wherein provision is made for double or duplicated substantially independent seals or closures to thereby insure an effective closure for the tank even in the event foreign matter should accidentally lodge on either valve seat.

Another object of the invention is to provide a simple and efficient operating mechanism for a tank car valve in which the mechanism is operated from the usual manhole at the top of the tank, the arrangement being such that the usual manhole cover cannot be placed in proper position unless and until the valve is in its closed position whereby all danger of leaving the discharge valve accidentally open when the car is in transit, is positively avoided.

Other objects of the invention will more clearly appear from the description and claims hereinafter following.

In the drawings forming a part of this specification, Figure 1 is a vertical, sectional view of portions of a tank car taken in a direction lengthwise thereof, parts being broken away in order to better accommodate the view on the sheet. The dotted lines indicate the positions assumed by certain parts of the operating mechanism when the valve is open. Figure 2 is a vertical, detail, sectional view corresponding substantially to the line 2—2 of Figure 1. Figure 3 is a horizontal, sectional view taken through the dome of the tank and corresponding sub-

stantially to the line 3—3 of Figure 1. Figure 4 is a vertical, sectional view corresponding substantially to the line 4—4 of Figure 1. Figure 5 is an enlarged, horizontal, sectional view taken substantially on the line 5—5 of Figure 1. And Figure 6 is a view corresponding to Figure 1 illustrating another embodiment of the valve mechanism.

Referring first to the construction illustrated in Figures 1 to 5 inclusive, the bottom tank sheet is indicated at 10, the same having an opening 11 therein to accommodate the various parts of the outlet or discharge valve arrangement. Secured to the under or outer side of said tank sheet 10 is an outlet pipe casting 12 having a discharge pipe proper 13. As will be understood by those skilled in the art, the pipe 13 is adapted to be closed by a reduction union such as shown at 14 in Figure 6 and a cap 15 applied to the union, such details not being shown in Figure 1 on account of lack of space. The casting 12 is also preferably annularly grooved as indicated at 16 so as to provide a weak point therein to allow for fracture in the event the depending discharge pipe engages an obstruction and avoid tearing out the other parts of the valve arrangement.

On its upper side, the casting 12 is suitably cut away as indicated at 17 to receive a double or compound valve seat bushing 18 formed of brass, bronze or other suitable desired material. Said bushing 18 may be held in position by peening or any other suitable manner not necessary to describe. As shown, said bushing 18 is formed near the bottom thereof with a conical valve seat indicated at 19 and above said valve seat with a second separated conical valve seat 20 of larger diameter. Cooperable with the valve seat 19 is a circular sleeve 21 having a conical valve proper 22 at its lower end conforming to the valve seat 19. Cooperable with the other valve seat 20 is a second sleeve 23 having a conical surface 24 arranged to seat on the valve seat 20.

The sleeve 23 is interiorly threaded at its upper end as indicated at 25 to thereby provide for the threaded attachment of a top cover 26, the latter having an elongated

socket 27 on the upper side thereof within which is received the lower end of the operating rod 28, the parts being secured together as by a pin 29. With the structure 5 described in the foregoing, it is evident that when the valve member 23 is properly seated on the valve seat 20, discharge of the contents is prevented.

The valve member 21 has a closed bottom 10 as indicated at 30 so that, when it is properly seated on the valve seat 19, discharge of the contents is positively prevented. Said sleeve 21 has an upwardly extending annular flange 31 provided at suitable intervals therearound 15 with radially inwardly extended ribs 32 and outwardly extended radial ribs 33. The ribs 32 form centering means for a spring 34 which seats at its lower end against the wall 30 and at its upper end against the cover or 20 cap 26 so that said spring normally tends to separate the two sleeves 21 and 23 vertically.

The outwardly extended radial ribs 33 overhang an inwardly extended annular shoulder 35 on the sleeve 23, the shoulders 25 defined by the ribs 33 being normally separated from the shoulder 35 when the two valve members are in operative position.

Secured to the under side of the sleeve 21 and depending vertically therefrom is a 30 guide or centering rod 36 which passes through a suitable perforation in a cross brace 37 mounted within the casting 12.

The operating rod 28 is extended upwardly within the dome of the tank car and 35 near the bottom thereof may be guided in a suitable bearing as indicated at 38, the latter being mounted on a suitable spider or brace 39 secured to the bottom of the tank. Preferably the bearing 38 will be formed at one 40 side with a pocket 40 open at its top and within which is vertically slidably more or less loosely a spider-like plunger 41 secured to the rod 28. With this arrangement it is evident that the plunger 41 operates in the 45 pocket 40 in the manner of a dashpot so as to prevent undesirable sudden snapping back of the valves into position under the influence of the return spring 42 mounted on the rod 28 and reacting against the collar 43 thereon and the washer 44 which in turn 50 engages the under side of the upper tank sheet 45.

Within the dome 46 of the tank car is secured a bracket 47, to which is pivotally connected one end of a lever 48, the latter having a suitable enlarged opening 49 therein to accommodate the operating rod 28. The latter has suitable nuts 50 and washer 51 thereon above the lever 48 so that, when 55 the latter is lifted, the rod 28 will also be lifted. At its outer end, the lever 48 is of substantially inverted U cross section as best indicated at 48^a in Figure 4, one depending arm being laterally enlarged as indicated at 60 48^b. Pivotally mounted within the section

48^a of the lever 48 as indicated at 52 is an operating handle 53 normally depending vertically as indicated in Figure 1. Said handle 53 is also of U cross section near its fulcrum as indicated at 54 and is adapted to work within the section 48^a of the lever 48. One side wall of the handle 53 has a laterally extended shoulder as indicated at 54^a in Figure 4 adapted to engage under the laterally enlarged arm 48^b. At its outer free end, the handle 53 is suitable formed with a grip 55 extending substantially at right angles to the main part of the handle 53 so that, when said handle is raised to the dotted position shown in Figure 1, the portion 55 will necessarily project upwardly through the opening of the manhole casting 56 which is normally closed by the cover 57.

The normal position of the parts is shown by the full lines in Figure 1. When the operating handle 53 is lifted, it is evident that it will engage with the U-shaped section 48^a and continued lifting of the handle 53 will consequently elevate the lever 48 and in turn the operating rod 28. As the lever 48 and handle 53 are moved upwardly, they engage a cam surface 58 on the lower end of a latch 59 suitably pivoted to a bracket 60 as indicated at 61. The pivot 61 is on an axis parallel to the general plane of the lever 48 and handle 53 so that, as the latter two are elevated, the latch 59 will be first swung to the right as indicated by the arrow α in Figure 4 and then will automatically slip back, under the influence of gravity, to the position shown in Figure 4 where the lever 48 and handle 53 engage upon and are held by a horizontal shoulder 62 on said latch 59. With this arrangement the rod 28 is positively held in its uppermost position and the valves open as will be understood. As hereinbefore mentioned, when the handle 53 is in its uppermost position, it is necessary that the manhole cover 57 be removed and vice versa the cover 57 cannot be replaced unless the handle is depressed and the handle can only be depressed by releasing the latch 59 which permits the lever 48 and rod 28 to move downwardly under the expansion of the spring 42.

When the rod 28 is elevated, the sleeve 23 will rise in unison therewith without unseating the valve or sleeve member 21 until the shoulder 35 engages the shouldered ribs 33 and thereafter both valve members will rise simultaneously. In returning to closed position, the valve member 21 will normally be projected as far downwardly as possible from the valve member 23 so that the valve proper 22 will normally engage the valve seat 19 in advance of the valve proper 24 engaging its seat 20. Should there be any obstruction on either of the valve seats 19 or 20, it is evident that there is sufficient yielding play between the two valve mem-

bers 21 and 23 to accommodate the necessary independent actions and hence a proper closure insured.

Another important feature of the invention resides in the following.

It frequently happens that, in the transportation of certain liquids, a certain amount of water accumulates in the outlet pipe, the water having a higher specific gravity than oil, for instance, and naturally separating from the oil at the bottom of the tank. In cold weather, such water collecting in the outlet pipe, if of sufficient quantity, may expand to such an extent as to either rupture or unseat valves of ordinary types heretofore employed. With our construction, however, it is evident that any reasonable amount of expansion of trapped water in the outlet pipe 13 can readily be accommodated by the inner or lower valve member 21 rising vertically within the other valve member 23 without danger of rupturing any of the parts or of unseating the member 23. As will be understood by those skilled in the art, the capacity of the spring 42 is made suitably greater than that of the spring 34 so as to insure positive return of the two valve members toward closed position.

In the form illustrated in Figure 6, the arrangement of outlet casting, operating rod and two sleeve members is the same as shown in Figure 1. In the arrangement of Figure 6, however, the compensating spring 134 is placed on the under side of the valve member 121. Said spring 134 seats, at its lower end, on a spider 70 which is secured to the lower end of the rod 136, the upper end of said rod being secured to the member 121.

The upper end of the spring 134 engages inwardly projecting lugs 71 located on the inner side of the depending outlet pipe. The spider 70 also acts as a centering guide for the valve member 121. The operation is the same as in connection with the mechanism shown in Figures 1 to 5, as will be understood without further detailed description.

Although we have herein shown and described what we now consider the preferred manner of carrying out the invention, the same is merely illustrative and all changes and modifications are contemplated that come within the scope of the claims appended hereto.

We claim:

1. In an apparatus of the character described, the combination with a tank having an outlet opening and two aligned valve seats adjacent thereto, one of larger diameter than the other; of a valve cooperable with the larger of said valve seats; a second valve cooperable with the smaller of said valve seats; means for directly lifting said larger valve from its seat; and cooperable means on said larger and smaller valves, normally

separated when the two valves are seated, engageable when the larger valve is lifted from its seat to thereby indirectly lift the smaller valve from its seat when the larger valve is lifted.

2. In an apparatus of the character described, the combination with a tank having an outlet opening and two valve seats adjacent thereto, one of said valve seats being further removed from the interior of the tank than the other; of a valve cooperable with the valve seat nearest the center of the tank; means for directly actuating said valve to move it to open position; a second valve cooperable with said valve seat which is farthest removed from the center of the tank; and means, operable when said first named valve is actuated directly, to actuate said second named valve to move the latter to open position.

3. In an apparatus of the character described, the combination with a tank having an outlet opening and two valve seats adjacent thereto, one of said valve seats being further removed from the interior of the tank than the other; of a valve cooperable with the valve seat nearest the center of the tank; means for directly actuating said valve to move it to open position; a second valve cooperable with said valve seat which is farthest removed from the center of the tank; means, operable when said first named valve is actuated directly, to actuate said second named valve to move the latter to open position; and means yieldingly interposed between said two valves for retaining the second named valve in its closed position when the first named valve is in its closed position.

4. In an apparatus of the character described, the combination with a tank having an outlet opening and two aligned valve seats adjacent thereto, one of larger diameter than the other; of a valve cooperable with the larger of said valve seats, said valve being of sleeve-like form with a closed top and provided with inturned shoulders; a second valve cooperable with the smaller of said valve seats and having outturned shoulders extending over said first named shoulders and normally spaced therefrom; and means for directly lifting said larger valve from its seat, the smaller valve being indirectly lifted from its seat by the larger valve.

5. In a tank car having a tank provided with a dome and a removable cover therefor and discharge opening in the bottom; the combination with a valve adapted to close said discharge opening; of a lift rod connected to said valve and extending into the dome; a lever pivotally mounted within the dome and having shouldered engagement with said rod; an operating handle pivotally attached to said lever, said handle being ar-

ranged to swing upwardly about its pivotal connection with said lever to lift the rod and open the valve; and a latch for holding said handle, lever, and rod in elevated position, said handle having a portion thereof extending within the cover opening when said handle is held by said latch.

6. In a tank car having a tank provided with a dome and a removable cover therefor and discharge opening in the bottom: the combination with a valve adapted to close said discharge opening; of a lift rod connected to said valve and extending into the dome; a lever pivotally mounted within the dome to swing about a horizontally extending axis and having operative engagement with said rod; an operating handle pivotally attached to said lever to also

swing about a horizontal axis, said operating handle normally depending in an inoperative position, said handle having shouldered engagement with said lever when elevated whereby the lever and lift rod will be also elevated; and means for holding said handle and lever in elevated position and with a portion of said handle within the cover opening, whereby the cover is only replaceable when said handle and lever are released.

In witness that we claim the foregoing we have hereunto subscribed our names this 21st day of March, 1921.

ARGYLE CAMPBELL.
ALBERT E. ZIMMER.

Witness:

UNA C. PERIN.
